X-RAY TUBE

Leopold Paroselli, 15 Anderson Ave., Demarest, N.J.

Continuation of abandoned design applications Ser. Nos. 61,567 and 61,568, July 29, 1960. This application Sept. 29, 1961, Ser. No. 66,960

Term of patent 14 years

(Cl. D26—8)

FIG. 1

FIG. 2

FIG. 3

FIG. 4

FIG. 5

FIG. 1 is a front elevational view of an X-ray tube showing my new design, wherein the ray emitting port is centrally disposed in the bottom of the lower transverse tubular member and the power supply connection is disposed on the side of the elongated middle upstanding neck or tubular portion;

FIG. 2 is a bottom plan view of the X-ray tube shown in FIG. 1;

FIG. 3 is a front view of an X-ray tube of the design shown in FIG. 1 wherein the ray emitting port is centrally disposed on the front of the lower transverse tubular member and the power supply connection is disposed on the back of the elongated neck or middle upstanding tubular portion;

FIG. 4 is a top plan view of the X-ray tube shown in FIG. 3;

FIG. 5 is an end elevational view thereof.

The portions not shown in each embodiment are like those shown except for the disposition of the port and the power supply connection as described.

This application is a continuation of design patent application Serial No. D. 61,567 and design patent application Serial No. D. 61,568, both filed July 29, 1960, and which are now abandoned.

I claim:

The ornamental design for an X-ray tube, substantially as shown and described.
